CLAIM

The ornamental design for a trolley as shown and described.

DESCRIPTION

FIG. 1 is a perspective view of a trolley showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is an opened perspective view thereof;

FIG. 8 is an opened front view thereof;

FIG. 9 is an opened rear view thereof;

FIG. 10 is an opened left side view thereof;

FIG. 11 is an opened right side view thereof; and,

FIG. 12 is an opened top view thereof.

The grey background shown in the drawings is for added contrast and ease of viewing the design and forms no part of the claimed design.
